UNITED STATES PATENT OFFICE.

ERNEST M. WHITE, OF DETROIT, MICHIGAN.

SPLASH-TROUGH.

1,202,937.

Specification of Letters Patent. Patented Oct. 31, 1916.

Application filed May 20, 1916. Serial No. 98,768.

To all whom it may concern:

Be it known that I, ERNEST M. WHITE, a citizen of the United States, and residing at Detroit, in the county of Wayne and State 5 of Michigan, have invented a new and Improved Splash-Trough, of which the following is a specification.

This invention relates to means for providing for a proper distribution of lubricating oil in the crank cases of internal combustion engines provided with main and auxiliary oil receptacles, and its object is to cause a portion of the oil splashed up from the auxiliary receptacles by the lower ends 10 of the connecting rods to be conveyed directly to the main oil receptacle of the engine and thereby prevent an excessive accumulation of lubricating oil at any part of the crank-case beneath the connecting rods. 15 This invention consists in an oil trough secured adjacent a side wall of the crank case of an internal combustion engine provided with internal reinforcing bars across the bottom of the crank case, the oil trough 20 being secured in such a manner as to be in the path of a portion of the lubricating oil splashed up from auxiliary oil receptacles in the crank case and so positioned that it will convey the oil to a main oil receptacle over 25 the top of the reinforcing bars within the crank case, said main oil receptacle being formed at one end of the crank case.

In the accompanying drawings, Figure 1 is an elevation of the engine of a well known automobile, one side of the crank case being broken away to show the oil conveyer or splash trough. Fig. 2 is an interior elevation of the splash trough. Fig. 3 is a vertical cross section of a crank case on the line 3-3 of Fig. 2. Figs. 4 to 9 inclusive are front elevations of various modifications of this improved device.

Similar reference characters refer to like parts throughout the several views.

The engine shown in Fig. 1 is of well known construction and is provided with an enlargement 1 at the rear end of the upper crank-case 2, and a similar enlargement 3 on the lower crank-case 4, the latter enlargement 45 constituting the main receptacle for lubricating oil. Oil is carried up from this main receptacle by the fly-wheel (not shown) and falls into the funnel 5, from which it flows forwardly through the pipe 6 to the 50 front end of the crank-case. The oil is

splashed up from the auxiliary receptacles 8, 9 and 10 by the connecting rods 11, 12 and 13. These auxiliary receptacles are usually formed in the removable bottom 14 of the lower crank case 4, which bottom is 60 held in position by screws 15 that extend up into threaded holes in the reinforcing bar 16. The rear transverse portion 17 of this reinforcing bar is back of the rear auxiliary receptacle 10 and usually causes a greater 65 depth of lubricant in these auxiliary receptacles than is necessary. It has been found that when the engine is running at even moderate speed, the entire crank case is filled with a heavy mist of oil which lubricates 70 the moving parts, and that this mist is heavier toward the rear of the engine, when the engine is mounted on a moving vehicle. For this reason an auxiliary receptacle for the rear connecting rod is seldom necessary. 75 The fly-wheel dips down into the lubricating oil in the main receptacle and also splashes lubricant up into the lower end of the rear cylinder. An excess of lubricant is usually conveyed to the front auxiliary receptacle through the pipe 6 until it reaches the level of the top of the reinforcing bar 16. When the oil is at this level the amount of lubricant splashed up into the lower ends of 80 the cylinders is usually so great that the combustion of that portion that is drawn up into the upper ends of the cylinders by the pistons causes an excessive deposit of carbon at the spark plugs and the valves. As a remedy for this trouble a trough 20 may be 85 secured to one or both sides of the crank case in such a manner that a portion of the lubricant splashed up by one or more of the connecting rods will be caught thereby and conveyed rearwardly above and beyond the 90 cross piece 17 to the main oil receptacle 3. These troughs may be made in many different ways and connected to the lower crank case in any desired manner, such as by means of rivets, bolts or by electric spot-welding. 100 The trough shown in Fig. 1 has one portion 20 secured to the side wall of the lower crank case and another portion 21, integral with the first, the trough being bent from a narrow strip of sheet metal.

Referring to Figs. 2 and 3, the trough is shown to be formed by a substantially triangular piece of sheet metal having an upper edge 23 bent away from the side wall 24 of the crank case. The structure also has a 110

body 25 and a laterally extending foot 26 that extends between the bottom 14 of the crank case and the reinforcing bar 16. The angle between the parts 25 and 26 is preferably such that the ridge 27 will be pressed against the side 24 sufficiently hard to prevent the lubricant running down between them.

In Fig. 4, the side plate 28 has a fin 29 secured to it in any desired manner and the foot 30 extends between the reinforcing bar 16 and the bottom 14, being firmly held by the bolts 15. The edge 31 of the fin 29 projects downwardly while in Fig. 5 the edge 32 of the trough 33 projects upwardly, the remainder of the structure being the same as that just described.

In the modification shown in Figs. 6 and 7, the horizontal portions 34 and 35 of the oil conveyers extend beneath the reinforcing bars 16 from the inside, and the troughs 36 and 37 are formed in the inclined portions 38 and 39 respectively. The upper edge 40 of the part 39 is shown to lie flat against the side 24 of the crank case while merely the upper edge of the part 38 engages this side.

In Fig. 8, the usual screw-threaded holes 41 in the bar 16 receive the bolts 42, having heads 43 to which the oil conveyer 44 is secured, and nuts 45 on the lower ends to hold the trough in position.

The conveyer shown in Fig. 9 consists of a side 48, a top plate 49 that extends between the adjacent flanges of the upper and lower crank cases, and a trough 50 formed by bending up the lower edge of the part 48.

While a number of modifications have been shown in the drawings, the invention is not limited thereto, but embraces all such single troughs as will receive the splashed up lubricating oil and convey it beyond the rein-

forcing bar within the crank case to the main oil receptacle.

I claim:

1. In an internal combustion engine, a crank-case having one end enlarged to constitute a main lubricating-oil receptacle and also having a bottom formed to hold oil into which the crank-ends of the connecting rods may dip to splash up the oil, a reinforcing bar within the crank-case, and an oil trough secured to a wall of the crank-case so as to receive a portion of the oil splashed up from said bottom and extending back beyond the said reinforcing bar to convey the oil thus received to the main oil receptacle.

2. In a multi-cylinder engine, a crank case formed with a main oil receptacle and having its bottom provided with a series of auxiliary oil receptacles, a cross bar extending across said crank case between the main receptacle and the auxiliary receptacles, and an inclined trough secured within the crank case adjacent one wall thereof and discharging oil splashed up from said auxiliary receptacles beyond said bar into said main receptacle.

3. In a multi-cylinder engine, a crank case formed with a main oil receptacle and having a removable bottom provided with a series of auxiliary oil receptacles, a reinforcing bar within the crank case and secured to the same around the bottom opening therein, the rear portion of said cross-bar extending between the main receptacle and the auxiliary receptacles and an inclined trough secured within the crank case adjacent one wall thereof and extending along a plurality of said auxiliary receptacles to receive oil splashed up from the plurality of said receptacles and convey it beyond said reinforcing bar to the main oil receptacle.

ERNEST M. WHITE.
